UNITED STATES PATENT OFFICE.

THOMAS B. JEFFERY, OF CHICAGO, ILLINOIS.

DESIGN FOR A VELOCIPEDe-HANDLE.

SPECIFICATION forming part of Design No. 22,760, dated August 29, 1893.

Application filed April 17, 1893. Serial No. 470,766. Term of patent 7 years.

To all whom it may concern:

Be it known that I, THOMAS B. JEFFERY, a citizen of the United States, residing at Chicago, county of Cook, and State of Illinois, 5 have invented and produced a certain new and original Design for a Velocipede-Handle, which is fully set forth in the following specification, reference being had to the accompanying drawings, forming a part thereof.

10 The drawings show in perspective a handle of my new design, Figure 1 being a rear view and Fig. 2, a front view.

This design relates to the form of the steering handles for velocipedes, and is characterized by the curvature of the handle-bars from their junction with the stem to the terminal hand-pieces.

15 Describing this form with respect to each bar, it is as follows:—From the central point or junction with the stem, the bar extends outward with an upward and obliquely rearward trend to the terminal hand-piece. The outward trend diminishes at an increasing rate, and the rearward trend increases, from 20 the stem junction, so that in direct plan the appearance of the two handle-bars would be that of a portion of an ellipse with the longer axis fore-and-aft through the stem junction

and cut parallel to the shorter axis between that axis and the end. The upward trend is 30 substantially uniform in a plane at an angle of about twenty degrees to a plane at right angles to the stem for about two-thirds of the length of the handle-bar from the stem junction, and there it commences to diminish, 35 causing an upward convexity beyond which the upward trend practically disappears, the remainder of the handle-bar and the hand-piece being practically horizontal.

The drawings represent the entire handle 40 in the ordinary position in which it appears in use. The combination of curvatures in vertical and horizontal planes, as above described, presents in this position a flowing outline and graceful appearance. 45

I claim—

The design for a velocipede handle herein shown and described.

In testimony whereof I have hereunto set my hand, at Chicago, Illinois, this 15th day of 50 April, A. D. 1893.

THOS. B. JEFFERY.
